REFRIGERATING APPARATUS

Graham S. McCloy, East Longmeadow, Mass., assignor to Westinghouse Electric & Manufacturing Company, East Pittsburgh, Pa., a corporation of Pennsylvania

Application December 16, 1936, Serial No. 116,102

12 Claims. (Cl. 62—115)

My invention relates to refrigerating apparatus wherein the quantity of refrigerant available for circulation is varied and has for an object to provide improved apparatus of this kind.

5 A further object of my invention is to provide improved means for varying the amount of refrigerant present in one or more evaporators.

A further object of the invention is to provide an improved unitary structure for varying the 10 amount of refrigerant available for circulation in a refrigerating system and for controlling the admission of refrigerant to one or more evaporators.

While not so limited, my invention is particularly applicable to two-temperature refrigerating 15 systems of the type disclosed and claimed in the copending application of Leslie B. M. Buchanan, Serial No. 15,003, filed April 6, 1935, and assigned to Westinghouse Electric & Manufacturing Company. The embodiment of my invention 20 closed hereinafter relates to a two-temperature system of the type shown in this application.

The foregoing and other objects are effected by my invention as will be apparent from the following description and claims taken in connection with the accompanying drawing forming a part of this application, in which:

Fig. 1 diagrammatically shows a two-temperature refrigerating system constructed and arranged in accordance with my invention, certain portions of which are shown enlarged; and,

Fig. 2 is a section taken along the line II—II of Fig. 1.

Referring to the drawing, a two-temperature refrigerator structure is shown generally at 10 and includes relatively low and high temperature zones or chambers 11 and 12, respectively. The chambers 11 and 12 are refrigerated by respective low and higher temperature evaporators 13 and 14. Refrigerant vaporized in the evaporators 13 and 14 is withdrawn through a conduit 15 by means of a compressor 16 driven by a motor 17, which define elements of a condensing unit, generally indicated at 18. The condensing unit 18 includes a condenser 19 cooled in any 45 suitable manner such as, for example, by a fan 21. The condenser 19 is connected to the compressor 16 for the reception of the compressed gas by means of a conduit 22.

Liquid refrigerant is conveyed from the condenser 19 through a conduit 23 to a structure 24 shown in enlarged scale and including a casing 25 which defines a reservoir 26 and a float valve structure 27. A partition 28 separates the float valve structure 27 into the reservoir 26 and a chamber 29. A conduit 31 serves to convey

condensed refrigerant from the float valve structure 27 to the evaporators 13 and 14 and is preferably connected to the evaporator 13, as shown. Further reference to the admission of refrigerant to the evaporators will be made hereinafter. 5

The structure 24 will now be described in detail. The upper portion of the casing 25 which is preferably of cylindrical form, defines the reservoir 26 for storing refrigerant during certain periods of operation of the apparatus. The condensed refrigerant conveyed by the conduit 23 is discharged into the reservoir 26. The chamber 29 at the bottom of the casing 25 receives condensed refrigerant from the reservoir 26 through a conduit 32 or through a passage 33 under control of a valve 34. The conduit 32 includes a portion 35 fixed preferably in the wall 28 and a movable portion 36 that is adjustable vertically with respect to the fixed portion 35. Preferably, the conduit portion 36 is threaded on the fixed 20 portion 35 and is rotatable with a stem 37 extending through the casing 25. The upper or movable conduit portion 36 is provided with one or more inlets 38 for the passage of refrigerant from the reservoir 26. 25

As shown best in Fig. 2, the stem 37 is preferably of hexagonal formation where it engages the conduit portion 36, so that rotation of the stem 37 effects rotation of the conduit portion 36. The conduit portion 36 is slidably mounted on 30 the stem 37 so that movement thereof axially of the stem 37 is permitted. The stem 37 includes an upper circular portion 39 rotatably mounted within a fitting 41 that is secured to the casing 25. An end 42 of the stem 37 is suitably formed 35 for engagement with an adjusting tool or wrench whereby the stem 37 may be rotated. Packing shown at 43 may be employed between the rounded portion 39 of the stem and the fitting 41 for preventing escape of refrigerant from the casing 25. A cap 44 is threaded on the fitting 41 for further preventing escape of refrigerant and is removable so that the end 42 of the stem 37 is accessible for adjustment. 40

The passage 33 is preferably formed in a cylindrical valve cage 45 secured in the wall 28. The valve cage includes inlet ports 46 for the passage of refrigerant from the reservoir 26 when the valve 34 is raised and seat 47 is formed in the valve cage 45 for the valve member 34. Means 45 is provided for actuating the valve 34 and preferably includes a solenoid winding 48 arranged exteriorly of the casing 25 and a core 49 disposed within the casing and subjected to the field produced by the winding 48. Energization of the 55

winding 48 effects upward movement of the core 49 and deenergization of the winding permits the core 49 to drop by gravity. The core 49 and valve 34 are secured together by a rod 51 so that the valve 34 is opened and closed as the core is raised and lowered by the action of the winding 48.

It will be understood that other suitable means may be provided for actuating the valve 34 and that the means disclosed is shown by way of example. However, by providing a solenoid in which the core is disposed inside the casing, it is not necessary to have any moving actuating member pass through the casing with the possibility of gas leakage. The embodiment disclosed is, therefore, desirable in this respect.

The float valve structure 27 of which the chamber 29 is a part includes a valve member 52 that is actuated by a float 53. The valve 52 cooperates with a seat 54 preferably formed in an outlet member 55 that is fixed in the casing 25. As shown, the conduit 31 is secured to the outlet member 55. The valve 52 is moved in opening and closing directions as the level of the liquid refrigerant in the chamber 29 rises and falls, respectively.

It will be understood that the charge of refrigerant in the system is such that when the reservoir 26 is empty, the evaporator 13 is substantially filled with refrigerant, and liquid refrigerant occupies a portion of the evaporator 14. When refrigerant is stored in the reservoir 26, the evaporator 13 contains a substantial amount of liquid refrigerant and the evaporator 14 is dry. As shown, the liquid supply conduit 31 admits refrigerant to the evaporators 13 and 14 in such manner that refrigerant flows into the evaporator 13 in preference to the evaporator 14. When the evaporator 13 is filled, overflow of refrigerant into the evaporator 14 is effected.

The amount of refrigerant present in the low temperature evaporator 13 during periods when it is operated may be varied by varying the amount of refrigerant in the reservoir 26. By adjusting the movable conduit member 36 upwardly, more refrigerant is stored in the reservoir 26 and less is present in the evaporator 13. The total charge of refrigerant in the system is circulated during periods when the valve 34 is in its open position and fills the evaporator 13 and a substantial portion of the evaporator 14.

Automatic control of the system may be effected by thermostats 56 and 57 disposed in the low and high temperature chambers 11 and 12 respectively. The thermostats 56 and 57 open and close their contacts in response to predetermined low and high temperatures in their respective chambers. The thermostat switches are shown at 58 and 59. It will be understood that the thermostat 57 is set to maintain a higher mean temperature in the chamber 12 than that maintained in the chamber 11 by the thermostat 56.

The source of power for the solenoid winding 48 and the motor 17 is represented by the line conductors L₁ and L₂. The motor 17 is energized by the thermostat switch 58 when closed in response to a predetermined high temperature in the chamber 11, the circuit for the motor 17 including a conductor 61. When the thermostatic switch 59 is closed, the motor 17 is energized by a circuit including a conductor 62 and the solenoid winding 48.

Operation

The positions of the various elements of the system as shown in the drawing indicate that the

temperatures in both chambers are below values at which their respective thermostatic switches close and, therefore, the motor 17 and compressor 16 are inactive. The reservoir 26 is empty which indicates that both evaporators 13 and 14 contain liquid refrigerant and that the previous cycle of operation effected refrigeration of the high temperature chamber 12.

Assume a rise in the low temperature chamber 11 to the value at which the thermostatic switch 10 58 is closed. The motor 17 is energized thereby and the solenoid winding 48 remains deenergized. Accordingly the valve 34 is in its closed position and operation of the compressor 16 is initiated. Refrigerant present in the evaporator 14 is vaporized and condensed in the condenser 19. The liquefied refrigerant is delivered for storage in the reservoir 26 until the level of the liquid rises to the overflow inlets 38 in the conduit 32. Some cooling of the high temperature evaporator 14 20 is effected at this time by the refrigerant vaporized therein but it is of short duration as the refrigerant is soon vaporized.

The pressure of the refrigerant in the evaporator 13 is reduced by the compressor 16 and the 25 vaporized refrigerant is conveyed through the evaporator 14 to the condenser 19 by the compressor 16. The liquid refrigerant delivered to the reservoir 26 overflows through the conduit structure 32 to the chamber 29 of the float valve 30 structure 27 and is admitted to the evaporator 13 under control of the float operated valve 54.

Operation of the compressor 16 progressively decreases the pressure and temperature of the refrigerant in the evaporator 13 to the value at 35 which thermostatic switch 56 opens to terminate operation of the compressor 16.

Assume a rise in temperature in the chamber 12 to the value at which the thermostatic switch 59 is closed. The motor 17 and the solenoid 48 40 are energized by a circuit including the conductor 62. Accordingly, operation of the compressor 16 is initiated and the valve 34 is raised from its seat 47. Refrigerant present in the reservoir 26 passes through the passage 33 to the chamber 29 and effects full opening of the valve 54. Refrigerant fills the evaporator 13 and overflows into the evaporator 14 and is rapidly vaporized due to the relatively high temperature thereof.

At this time the entire charge of refrigerant 50 is available for circulation so that both evaporator 13 and 14 contain liquid refrigerant. As the evaporator 13 is substantially filled with condensed refrigerant, a seal is defined for preventing refrigerant vaporized in the high temperature evaporator 14 from condensing in the low temperature evaporator 13. Vaporization in the low temperature evaporator 13 is not effected at this time as the temperature of the evaporator 13 is lower than the temperature of vaporization corresponding to the pressure of the contained refrigerant.

The compressor 16 operates to decrease the pressure and temperature of the refrigerant in the evaporator 14 until the thermostat 57 opens 65 its switch 59 in response to a predetermined low temperature within the chamber 12, at which time the compressor 16 is stopped and the valve 34 is moved to its closed position due to the de-energization of the winding 48. The apparatus 70 is now in the position shown in the drawing.

One or the other of the thermostats 56 and 57 may be given preference when both call for cooling. As shown, the thermostat 56 is the preferred thermostat due to the fact that the con- 75

ductor 61 defines a shunt across the winding 48 when both thermostatic switches 58 and 59 are closed, and, therefore, the winding 48 is deenergized and the valve 34 is in its closed position. 5
Accordingly, refrigerant is stored in the reservoir 26 and condensed refrigerant is present for vaporization in the low temperature evaporator 13 only. It will be understood that preference may be given to the high temperature thermostat 10 57 if desired.

I have shown my improved system applied for refrigerating two zones of a refrigerator and including two evaporating elements but it is to be understood that it may be applied to single evaporator systems in which the amount of liquid refrigerant present in the low side thereof is to be varied.

From the foregoing, it will be apparent that I have provided an improved refrigerating system having means for withholding condensed refrigerant from circulation, wherein the amount of refrigerant withheld may be readily varied and wherein a compact unitary structure is provided for varying the quantity of refrigerant available for circulation and for controlling its admission to the evaporator or evaporators. While I have shown a refrigerating system of the compressor-condenser-expander cycle, it will be understood that my invention is applicable to other types 30 of refrigerating systems.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

40 What I claim is:

1. In a two-temperature refrigerating system, the combination of a pair of evaporator elements, means for condensing refrigerant vaporized in the evaporator elements, means for conveying the condensed refrigerant to the evaporator elements for vaporization and means for withholding a predetermined quantity of condensed refrigerant from circulation at certain times during the operation of the system, whereby condensed refrigerant is delivered to only one of the evaporator elements at that time, said refrigerant withholding means including an adjustment for varying the amount of refrigerant that may be withheld from said one evaporator element.

55 2. In a refrigerating system, the combination of an evaporator having first and second portions, means for condensing refrigerant vaporized in the evaporator, means for conveying the condensed refrigerant to the evaporator for vaporization and means for withholding a predetermined quantity of condensed refrigerant from circulation whereby the effective charge of refrigerant in the system is reduced and condensed refrigerant is delivered to the first evaporator portion only, said refrigerant withholding means including a casing structure for defining a reservoir for the withheld refrigerant and an adjusting device for varying the storing capacity of the reservoir and readily accessible exteriorly of the casing.

70 3. In a refrigerating system, the combination of an evaporator having first and second portions, means for condensing refrigerant vaporized in the evaporator, means for conveying the condensed refrigerant to the evaporator for vaporization and means for withholding a predetermined quantity of condensed refrigerant from circulation whereby the effective charge of refrigerant in the system is reduced and condensed refrigerant is delivered to the first evaporator portion only, said refrigerant withholding means including a casing structure for defining a reservoir for the withheld refrigerant and an adjusting device for varying the storing capacity of the reservoir and readily accessible exteriorly of the casing.

75

zation and means for withholding a predetermined quantity of condensed refrigerant from circulation whereby the amount of refrigerant present in the evaporator is reduced and substantially fills the first evaporator portion; said means including a casing structure for defining a reservoir for the withheld refrigerant, an expansion device for the condensed refrigerant disposed beneath the reservoir for receiving condensed refrigerant therefrom and an adjusting device for 10 varying the storing capacity of the reservoir and extending exteriorly of the reservoir.

4. In refrigerating apparatus, the combination of an evaporator, means for condensing refrigerant vaporized in the evaporator, a casing defining a reservoir for receiving condensed refrigerant from the condensing means and an expansion device disposed at a lower level than the reservoir for controlling the admission of refrigerant to the evaporator, a conduit communicating with the reservoir and the expansion device, said conduit having its inlet disposed at variable elevations within the reservoir, means for adjusting the elevation of the conduit inlet, valve means controlling communication between the reservoir and the expansion device and opened and closed for respectively releasing refrigerant from the reservoir and for storing the same therein, and means for actuating said valve.

5. The combination as claimed in claim 4 30 wherein the valve actuating means is disposed at least in part exteriorly of the casing.

6. The combination as claimed in claim 4 35 wherein the valve actuating means is electrically operated.

7. In two temperature refrigerating apparatus, the combination of low and high temperature evaporators, means for condensing refrigerant vaporized in the evaporators and means for conveying the condensed refrigerant to the evaporators and comprising means for decreasing or increasing the effective charge of refrigerant whereby condensed refrigerant is supplied to the low temperature evaporator only for vaporization at low pressure or is supplied to both evaporators for vaporization primarily in the high temperature evaporator at relatively high pressure, said charge varying means including a reservoir for condensed refrigerant, an expansion device for receiving condensed refrigerant from the reservoir and for controlling its admission to the evaporators, a conduit providing communication between an upper portion of the reservoir and the expansion device and having at least a portion thereof adjustable, means for adjusting said conduit portion upwardly and downwardly in the reservoir, means providing communication between a lower portion of the reservoir and the expansion device, a valve associated with the last-named means, and means for opening and closing said valve.

8. In a refrigerating system, the combination of first and second evaporators, means for condensing refrigerant vaporized in the evaporators, a casing defining a reservoir and a float valve structure therebeneath, said float valve controlling the admission of refrigerant to the evaporator, means for conveying the condensed refrigerant to the reservoir, an overflow conduit communicating with an elevated portion of the reservoir for conveying refrigerant to the float valve structure, said overflow conduit including an adjustable portion, means for adjusting the conduit portion upwardly and downwardly whereby the storage capacity of the reservoir is varied, 75

means defining a passage for providing communication between a bottom portion of the reservoir and the float valve structure, a valve controlling the passage, and means responsive to demands for refrigeration by the evaporators for opening and closing the valve, whereby as the valve is closed refrigerant is stored in the reservoir and condensed refrigerant is supplied to the first evaporator only and when the valve is open the stored refrigerant is released and substantially fills the first evaporator and at least a portion of the second evaporator.

9. In refrigerating apparatus, the combination of a unitary casing structure defining a float valve chamber and a reservoir thereabove, a conduit providing communication between the float valve chamber and an upper portion of the reservoir, said casing structure including a passage providing communication between a bottom portion of the reservoir and the float valve chamber, a valve controlling said passage, means for actuating the valve, means for admitting condensed refrigerant to the reservoir and means for conveying condensed refrigerant from the float chamber for vaporization.

10. In refrigerating apparatus, the combination of a unitary casing structure defining a float valve chamber and a reservoir thereabove, a conduit providing communication between the float valve chamber and an upper portion of the reservoir, means for adjusting said conduit upwardly and downwardly with respect to the reservoir, said casing structure including a passage providing communication between a bottom portion of the reservoir and the float valve chamber, a valve controlling said passage, means for actuating the valve, means for admitting condensed re-

frigerant to the reservoir and means for conveying condensed refrigerant from the float chamber for vaporization.

11. In refrigerating apparatus, the combination of an evaporator, means for condensing refrigerant vaporized in the evaporator, a casing defining a reservoir for receiving condensed refrigerant from the condensing means, means for conveying the refrigerant from said casing to the evaporator and including a conduit, said conduit having its inlet disposed at variable elevations within the reservoir, means for adjusting the elevation of the conduit inlet, valve means controlling communication between the reservoir and said conveying means, and opened and closed for respectively releasing refrigerant from the reservoir and for storing the same therein, and means for actuating said valve.

12. In refrigerating apparatus, the combination of an evaporator, means for condensing refrigerant vaporized in the evaporator, a casing defining a reservoir for receiving condensed refrigerant from the condensing means, means for conveying refrigerant from the casing to the evaporator and including a conduit structure, said structure having a conduit portion secured to the casing, and a rotatable conduit portion threaded to the fixed conduit portion and having an upper portion thereof in communication with the reservoir, a rotatable stem extending exteriorly of the casing and splined to the rotatable conduit portion, means defining a passage for providing communication between a bottom portion of the reservoir and said conveying means, a valve controlling the passage and means for actuating said valve.

GRAHAM S. McCLOY.
